(57) **CLAIM**

The ornamental design for an end cap, as shown and described.

DESCRIPTION

FIG. 1 is a perspective front view of an end cap showing my new design;

FIG. 2 is a perspective back view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a first perspective view of the end cap in use; and,

FIG. 10 is a second perspective view of the end cap in use.

Broken lines illustrate environment elements of the end cap in use and/or portions of the end cap that form no part of the claimed design.
